(57) **ABSTRACT**

A method of installing an adapter, a kit including an adapter, and an adapter are disclosed. The adapter includes a first connector, a second connector, and a component adapted for facilitating the second connector to electrical communicate with a portion of a plurality of pins or sockets of the first connector in a predetermined pinout. The first connector has a first plurality of pins or sockets. The second connector has a plug and a socket. Each of the plug and socket has a second plurality of pins or sockets. One of the plug and the socket of the second connector is adapted to mechanically communicate with a first portion of a third plurality of electrical conductors to facilitate electrical communication. The other of the plug and the socket of the second connector is adapted to electrically communicate with a first portion of the first plurality of pins or sockets of the first connector.

**METHOD, KIT, AND AN ASSOCIATED
ADAPTOR, USABLE WITH A HOSPITAL BED**

This is a continuation-in-part of application Ser. No. 12/459,484, filed Jul. 2, 2009, now abandoned and the entirety of the foregoing application is incorporated herein by reference.

Aspects of embodiments and embodiments of the present invention are directed to one or more of a method of installing an adapter, a kit including an adapter, and an adapter. The adapter includes a first connector, a second connector, and a component adapted for facilitating the second connector to electrical communicate with a portion of a plurality of pins or sockets of the first connector in a first predetermined pinout.

BACKGROUND OF INVENTION

Often associated with a hospital bed there is preselected equipment in electrical communication with a nurse call station. The preselected equipment can include controls to enable, for example, a patient, nurse, or orderly to adjust the bed, operate room lighting, and select entertainment as well as a speaker for entertainment and nurse call system intercom audio. A plurality of electrical conductors, which can be in the form of one or more cables, facilitate electrical communication of the preselected equipment and the nurse call station through a connector. The connector, which has a plurality of pins or sockets, is typically mounted on a lower portion of a wall at about shin level while the nurse call station is typically mounted on an upper portion of a wall at about eye level. Through the normal movement of a hospital bed, that can involve removing and replacing a complement to the connector, the connector can become worn. Sometimes when the movement of a hospital bed is done in haste without removing the complement to the connector from the connector, the wear of the connector is accelerated, or the connector is damaged. Whether worn or damaged, the connector is eventually replaced by skilled personal typically taking several hours. During those hours, the skilled personal records the connection sequenced of the plurality of electrical conductors to the nurse call station, disconnects the plurality of electrical conductors from the nurse call station, removes the worn or damaged connector and its associated plurality of electrical conductors, provides a new connector and its associated plurality of electrical conductors, fishes the associated plurality of electrical conductors to the nurse call station, reconnects the associated plurality of electrical conductors to the nurse call station in the recorded connection sequenced, and replaces the connector and the nurse call station.

BRIEF SUMMARY OF INVENTION

The problems of skilled personal requiring several hours to replace and/or unskilled and semi-skilled personal being incapable of replacing a connector having a plurality of pins or sockets electrically communicating through a plurality of electrical conductors in a predetermined pinout to facilitate electrical communication among preselected equipment associated with a preselected hospital bed (e.g., Stryker Medical, Portage, Mich., USA: see e.g., <http://www.stryker.com/en-us/products/PatientHandlingEMSSandEvacuationEquipment/Beds/index.htm> and <http://www.stryker.com/stellent/groups/jsp/documents/adacct/056403.pdf> as well as Hill-Rom Corporate Offices, Batesville, Ind., USA: <http://www.hill-rom.com/usa/index.asp> and <http://www.hill-rom.com/usa/PDF/CTG271.pdf>) and a preselected nurse station (see e.g., Rauland-Borg Corporation,

2

Mount Prospect, Ill., USA: <http://www.rauland.com/index.cfm>; Jeron Electronic Systems, Inc., Chicago, Ill., USA: <http://www.jeron.com/>; TekTone® Sound & Signal Mfg., Inc., Franklin, N.C., USA: <http://www.tektone.com/index.htm>; and Hill-Rom Corporate Offices, Batesville, Ind., USA: http://www.hill-rom.com/usa/NaviCare_Nurse-Call.htm that are merely four out of a possibility of about 25) are solved by any one of a method of installing an adapter, a kit including an adapter, and an adapter. The adapter includes a first connector, a second connector, and a component adapted for facilitating the second connector to electrical communicate with a portion of a plurality of pins or sockets of the first connector in a first predetermined pinout.

Some aspects of embodiments and embodiments of the present invention meet these and other needs by providing, without limitation, an adapter 10 including a first connector 12, a second connector 14, and a component 16 adapted to facilitate electrical communication between the second connector 14 and a portion 18 of a plurality of the pins or sockets 22 of the first connector 12 in a first predetermined pinout. As noted, the first connector 12 has a first plurality of pins or sockets 22. The second connector 14 has a plug 24 and a socket 26. Each of the plug 24 and socket 26 has a second plurality of pins or sockets 30. One of the plug 24 and the socket 26 of the second connector 14 is adapted to mechanically communicate with a first portion 17 of a third plurality of electrical conductors 32 to facilitate electrical communication. The other of the plug 24 and the socket 26 of the second connector 14 is adapted to electrically communicate with the first portion 18 of the first plurality of pins or sockets 22 of the first connector 12 in a first predetermined pinout.

Other aspects of embodiments and embodiments of the present invention meet these and other needs by providing, without limitation, a kit 50 including an adapter 10 and, optionally, a tool 48. The adapter 10 includes a first connector 12, a second connector 14, and a component 16 adapted to facilitate electrical communication between the second connector 14 and a portion 18 of a plurality of the pins or sockets 22 of the first connector 12 in a first predetermined pinout. As noted, the first connector 12 as a first plurality of pins or sockets 22. The second connector 14 has a plug 24 and a socket 26. Each of the plug 24 and socket 26 has a second plurality of pins or sockets 30. One of the plug 24 and the socket 26 of the second connector 14 is adapted to mechanically communicate with a first portion 17 of a third plurality of electrical conductors 32 to facilitate electrical communication. The other of the plug 24 and the socket 26 of the second connector 14 is adapted to electrically communicate with a first portion 18 of the first plurality of pins or sockets 22 of the first connector 12 in a first predetermined pinout. The tool 48 is adapted to facilitate a mechanical communication of a third plurality of electrical conductors 32 to one of a plug 24 and a socket 26 of a second connector 14 to facilitate electrical communication of the third plurality of electrical conductors 32 with a third portion 60 of a first plurality of pins or sockets 22 of a first connector 12. 65

Still other aspects of embodiments and embodiments of the present invention meet these and other needs by providing,

without limitation, a method for replacing a connector adapted to facilitate the electrical communication among pre-selected equipment 34 associated with a preselected hospital bed 36 and a preselected nurse station. The method includes providing an adapter 10 including a first connector 12, a second connector 14, and a component 16 adapted to facilitate electrical communication between the second connector 14 and a first portion 18 of a plurality of the pins or sockets 22 of the first connector 12 in a first predetermined pinout and communicating the third plurality of electrical conductors 32 to the one of the plug 24 and the socket 26 of the second connector 14. As noted, the first connector 12 as a first plurality of pins or sockets 22. The second connector 14 has a plug 24 and a socket 26. Each of the plug 24 and socket 26 has a second plurality of pins or sockets 30. One of the plug 24 and the socket 26 of the second connector 14 is adapted to mechanically communicate with a first portion 17 of a third plurality of electrical conductors 32 to facilitate electrical communication. The other of the plug 24 and the socket 26 of the second connector 14 is adapted to electrically communicate with a first portion 18 of the first plurality of pins or sockets 22 of the first connector 12. The component 16 includes a plurality of conductors 28 adapted for facilitating the other of the plug 24 and the socket 26 of the second connector 14 to electrically communicate with the first portion 18 of the first plurality of pins or sockets 22 of the first connector 12 in a first predetermined pinout. The tool 48 is adapted to facilitate a mechanical communication of a third plurality of electrical conductors 32 to one of a plug 24 and a socket 26 of a second connector 14 to facilitate electrical communication of the third plurality of electrical conductors 32 with a first portion of a first plurality of pins or sockets 22 of a first connector 12.

Accordingly, some aspects of embodiments and embodiments of the present invention provide an adapter 10 further might include guidance indicia 20 adapted to provide guidance for the mechanical communication of the third plurality of electrical conductors 32 to the one of the plug 24 and the socket 26 of the second connector 14 to facilitate electrical communication of the third plurality of electrical conductors 32 with the first portion 18 of the first plurality of pins or sockets 22 of the first connector 12 in the predetermined pinout to facilitate electrical communication among pre-selected equipment 34 associated with a preselected hospital bed 36 and a preselected nurse call station 40.

Some other aspects of embodiments and embodiments of the present invention provide further including a third connector 14' or even a fourth connector 14''. The third connector 14' has a plug 24' and a socket 26'. Each of the plug 24' and socket 26' has a second plurality of pins or sockets 30'. One of the plug 24' and socket 26' of the third connector 14' is adapted to mechanically communicate with a second portion 17' of a third plurality of electrical conductors 32 to facilitate electrical communication. The other of the plug 24' and the socket 26' of the third connector 14' is adapted to electrically communicate with a second portion 18' of the first plurality of pins or sockets 22 of the first connector 12. The component 16 includes a plurality of conductors 28 adapted for facilitating the other of the plug 24 and the socket 26 of the third connector 14' to electrically communicate with the second portion 18' of the first plurality of pins or sockets 22 of the first connector 12 in a first predetermined pinout. The fourth connector 14'' has a plug 24'' and a socket 26''. Each of the plug 24'' and socket 26'' has a third plurality of pins or sockets 30''. One of the plug 24'' and socket 26'' of the fourth connector 14'' is adapted to mechanically communicate with a third portion 17'' of a third plurality of electrical conductors 32 to facilitate

electrical communication. The other of the plug 24' and the socket 26' of the fourth connector 14' is adapted to electrically communicate with a third portion 18'' of the first plurality of pins or sockets 22 of the first connector 12. Again, the component 16 includes a third plurality of conductors 28 adapted for facilitating the other of the plug 24 and the socket 26 of the fourth connector 14'' to electrically communicate with the third portion 18'' of the first plurality of pins or sockets 22 of the first connector 12 in a first predetermined pinout.

Still yet other aspects of embodiments and embodiments of the present invention provide that the first connector 12 be a D-subminiature connector. As another example, aspects of embodiments and embodiments of the present invention, any one of the second connector 14, the third connector 14', the fourth connector 14'', or any combinations thereof, includes an insulation-displacement connector (IDC connector) or insulation-piercing connectors (IPC connector).

As yet another example, aspects of embodiments and embodiments, the component 16 comprising a plurality of conductors comprises a printed circuit board (PCB).

As still yet another example, aspects of embodiments and embodiments, the indicia 20 adapted to provide guidance comprises a cross-reference between the pins or sockets the second connector 14 and a color of the third plurality of electrical conductors 32.

As even still yet another example, aspects of embodiments and embodiments, the third plurality of electrical conductors 32 comprise a plurality of cables and the indicia 20 adapted to provide guidance comprises a cross-reference between a color of the electrical conductors of each cable of the plurality of cables and the pins or sockets each of the second 14, third 14', and fourth 14'' connectors.

Numerous other aspects of embodiments, embodiments, features, and advantages of the present invention will appear from the following detailed description and the accompanying drawings. In the description and/or the accompanying drawings, reference is made to exemplary aspects of embodiments and/or embodiments of the invention which can be applied individually or combined in any way with each other. Such aspects of embodiments and/or embodiments do not represent the full scope of the invention. Reference should therefore be made to the claims herein for interpreting the full scope of the invention. In the interest of brevity and conciseness, any ranges of values set forth in this specification contemplate all values within the range and are to be construed as support for claims reciting any sub-ranges having endpoints which are real number values within the specified range in question. By way of a hypothetical illustrative example, a disclosure in this specification of a range of from 1 to 5 shall be considered to support claims to any of the following ranges: 1-5; 1-4; 1-3; 1-2; 2-5; 2-4; 2-3; 3-5; 3-4; and 4-5. Also in the interest of brevity and conciseness, it is to be understood that such terms as "is," "are," "includes," "having," "comprises," and the like are words of convenience and are not to be construed as limiting terms and yet may encompass the terms "comprises," "consists essentially of," "consists of," and the like as is appropriate.

These and other aspects, advantages, and salient features of the present invention will become apparent from the following detailed description, the accompanying drawings, and the appended claims.

BRIEF DESCRIPTION OF DRAWINGS

The drawings referenced herein form a part of the specification. Features shown in the drawings are meant to be illustrative of some, but not all, embodiments of the invention,

unless otherwise explicitly indicated, and implications to the contrary are otherwise not to be made. Although like reference numerals correspond to similar, though not necessarily identical, components and/or features in the drawings, for the sake of brevity, reference numerals or features having a previously described function may not necessarily be described in connection with other drawings in which such components and/or features appear.

FIG. 1 is a schematic illustrating an adapter constructed according to aspects of embodiments and/or embodiments of the present invention;

FIG. 2 is a schematic illustrating a use of the adapter of FIG. 1 to electrically communicate with a station electrically communicating with a plurality of peripherals according to aspects of embodiments and/or embodiments of the present invention;

FIG. 3 is a schematic illustrating details of the adapter of FIG. 1 according to aspects of embodiments and/or embodiments of the present invention;

FIG. 4 is a schematic illustrating a use of the adapter of FIG. 1 to electrically communicate with a nurse call station electrically communicating with a plurality of hospital peripherals according to aspects of embodiments and/or embodiments of the present invention;

FIG. 5 is a schematic illustrating an exploded view of the adapter of FIG. 1 according to aspects of embodiments and/or embodiments of the present invention;

FIG. 6 is a schematic illustrating a predetermined pinout for the adapter of FIG. 1 according to aspects of embodiments and/or embodiments of the present invention;

FIG. 7 is a schematic illustrating an exploded view of an alternative adapter according to aspects of embodiments and/or embodiments of the present invention; and

FIG. 8 is a schematic illustrating a predetermined pinout for the alternative adapter of FIG. 7 according to aspects of embodiments and/or embodiments of the present invention.

DETAILED DESCRIPTION

In the following detailed description of exemplary aspects of embodiments and embodiments of the invention, reference is made to the accompanying drawings that form a part hereof, and in which are shown by way of illustration specific aspects of embodiments and embodiments in which the invention may be practiced. While these aspects of embodiments and embodiments are described in sufficient detail to enable those skilled in the art to practice the invention, it will nevertheless be understood that no limitation of the scope of the present disclosure is thereby intended. Alterations and further modifications of the features illustrated herein, and additional applications of the principles illustrated herein, which would occur to one skilled in the relevant art and having possession of this disclosure, are to be considered within the scope of this disclosure. Specifically, other aspects of embodiments and embodiments may be utilized, logical changes (e.g., without limitation, any one or more of chemical, compositional, materials, electrical, electrochemical, electromechanical, electro-optical, mechanical, optical, physical, physicochemical, . . . and the like) and other changes may be made without departing from the spirit or scope of the present invention. Accordingly, the following detailed description is not to be taken in a limiting sense, and the scope of aspects of embodiments and embodiments of the present invention are defined by the appended claims. It is also understood that terms such as "top," "bottom," "outward," "inward," and the like are words of convenience and are not to be construed as limiting terms.

Referring now to the drawings in general and FIG. 1 and FIG. 2 in particular, a perspective views of an adapter 10 is shown. As shown in FIG. 1, FIG. 3, FIG. 6, and FIG. 8, adapter 10 includes a first connector 12, a second connector 14, and a component 16 adapted to facilitate electrical communication between the second connector 14 and a portion 18 (see FIG. 6 and FIG. 8) of a plurality of the pins or sockets 22 of the first connector 12 in a first predetermined pinout. As noted and can be seen in FIG. 1, FIG. 3, FIG. 6, and FIG. 8, the first connector 12 has a first plurality of pins or sockets 22. As can be seen in FIG. 3, the second connector 14 has a plug 24 and a socket 26. Each of the plug 24 and socket 26 has a second plurality of pins or sockets 30. As can be seen in FIG. 1 and FIG. 3, one of the plug 24 and the socket 26 of the second connector 14 is adapted to mechanically communicate with a first portion 17 of a third plurality of electrical conductors 32 to facilitate electrical communication. As can be seen in FIG. 6 and FIG. 8, the other of the plug 24 and the socket 26 of the second connector 14 is adapted to electrically communicate with a first portion 18 of the first plurality of pins or sockets 22 of the first connector 12. Also as can be seen in FIG. 6 and FIG. 8, the component 16 includes a plurality of conductors 28 adapted for facilitating the other of the plug 24 and the socket 26 of the second connector 14 to electrically communicate with the first portion 18 of the first plurality of pins or sockets 22 of the first connector 12 in a first predetermined pinout.

Other aspects of embodiments and embodiments of the present invention meet these and other needs by providing, without limitation, a kit 50 including an adapter 10 and, optionally, a tool 48. The adapter 10 includes a first connector 12, a second connector 14, and a component 16 adapted to facilitate electrical communication between the second connector 14 and a portion 18 of a plurality of the pins or sockets 22 of the first connector 12 in a first predetermined pinout. As noted, the first connector 12 has a first plurality of pins or sockets 22. The second connector 14 has a plug 24 and a socket 26. Each of the plug 24 and socket 26 has a second plurality of pins or sockets 30. One of the plug 24 and the socket 26 of the second connector 14 is adapted to mechanically communicate with a first portion 17 of a third plurality of electrical conductors 32 to facilitate electrical communication. The other of the plug 24 and the socket 26 of the second connector 14 is adapted to electrically communicate with a first portion 18 of the first plurality of pins or sockets 22 of the first connector 12. The component 16 includes a plurality of conductors 28 adapted for facilitating the other of the plug 24 and the socket 26 of the second connector 14 to electrically communicate with the first portion 18 of the first plurality of pins or sockets 22 of the first connector 12 in a first predetermined pinout. The tool 48 is adapted to facilitate a mechanical communication of a third plurality of electrical conductors 32 to one of a plug 24 and a socket 26 of a second connector 14 to facilitate electrical communication of the third plurality of electrical conductors 32 with a first portion of a first plurality of pins or sockets 22 of a first connector 12.

Still other aspects of embodiments and embodiments of the present invention meet these and other needs by providing, without limitation, a method for replacing a connector 60 adapted to facilitate the electrical communication among pre-selected equipment 34 associated with a preselected hospital bed 36 and a preselected nurse station. The method includes providing an adapter 10 including a first connector 12, a second connector 14, and a component 16 adapted to facilitate electrical communication between the second connector 14 and a portion 18 of a plurality of the pins or sockets 22 of the first connector 12 in a first predetermined pinout and

communicating the third plurality of electrical conductors 32 to the one of the plug 24 and the socket 26 of the second connector 14. As noted, the first connector 12 as a first plurality of pins or sockets 22. The second connector 14 has a plug 24 and a socket 26. Each of the plug 24 and socket 26 has a second plurality of pins or sockets 30. One of the plug 24 and the socket 26 of the second connector 14 is adapted to mechanically communicate with a first portion 17 of a third plurality of electrical conductors 32 to facilitate electrical communication. The other of the plug 24 and the socket 26 of the second connector 14 is adapted to electrically communicate with a first portion 18 of the first plurality of pins or sockets 22 of the first connector 12. The component 16 includes a plurality of conductors 28 adapted for facilitating the other of the plug 24 and the socket 26 of the second connector 14 to electrically communicate with the first portion 18 of the first plurality of pins or sockets 22 of the first connector 12 in a first predetermined pinout. The tool 48 is adapted to facilitate a mechanical communication of a third plurality of electrical conductors 32 to one of a plug 24 and a socket 26 of a second connector 14 to facilitate electrical communication of the third plurality of electrical conductors 32 with a first portion of a first plurality of pins or sockets 22 of a first connector 12.

  - 17 - BLU/BLK (Blue/Black)
  - 18 - GRN/WHT (Green/White)
-

Accordingly, some aspects of embodiments and embodiments of the present invention provide an adapter 10 further might include guidance indicia 20 adapted to provide guidance for the mechanical communication of the third plurality of electrical conductors 32 to the one of the plug 24 and the socket 26 of the second connector 14 to facilitate electrical communication of the third plurality of electrical conductors

32 with the first portion 18 of the first plurality of pins or sockets 22 of the first connector 12 in the predetermined pinout to facilitate electrical communication among preselected equipment 34 associated with a preselected hospital bed 36 and a preselected nurse call station 40 as shown in FIG. 4. The table above is an example of such guidance to indicia 20.

As can be seen in FIG. 1, FIG. 3, and FIG. 6, some other aspects of embodiments and embodiments of the present invention provide further including a third connector 14' and a fourth connector 14". The third connector 14' has a plug 24' and a socket 26'. Each of the plug 24' and socket 26' has a second plurality of pins or sockets 30'. One of the plug 24' and socket 26' of the third connector 14' is adapted to mechanically communicate with a second portion 17' of a third plurality of electrical conductors 32 to facilitate electrical communication. The other of the plug 24' and the socket 26' of the third connector 14' is adapted to electrically communicate with a second portion 18' of the first plurality of pins or sockets 22 of the first connector 12. The component 16 includes a plurality of conductors 28 adapted for facilitating the other of the plug 24 and the socket 26 of the third connector 14' to electrically communicate with the second portion 18' of the first plurality of pins or sockets 22 of the first connector 12 in a first predetermined pinout. The fourth connector 14" has a plug 24" and a socket 26". Each of the plug 24" and socket 26" has a third plurality of pins or sockets 30". One of the plug 24" and socket 26" of the fourth connector 14" is adapted to mechanically communicate with a third portion 17" of a third plurality of electrical conductors 32 to facilitate electrical communication. The other of the plug 24" and the socket 26" of the fourth connector 14" is adapted to electrically communicate with a third portion 18" of the first plurality of pins or sockets 22 of the first connector 12. Again, the component 16 includes a third plurality of conductors 28 adapted for facilitating the other of the plug 24 and the socket 26 of the fourth connector 14" to electrically communicate with the third portion 18" of the first plurality of pins or sockets 22 of the first connector 12 in a first predetermined pinout.

As can be seen in FIG. 1, FIG. 3, FIG. 6, and FIG. 8, still yet other aspects of embodiments and embodiments of the present invention provide that the first connector 12 be a D-subminiature connector.

As another example as shown in FIG. 1, FIG. 3, FIG. 5, FIG. 6, FIG. 7, and FIG. 8, aspects of embodiments and embodiments of the present invention, any one of the second connector 14, the third connector 14', the fourth connector 14", or any combinations thereof, includes an insulation-displacement connector (IDC connector) or insulation-piercing connectors (IPC connector). Corresponding tooling 48 such, MTA-100 tooling is commercially available from Carlton-Bates of Little Rock, Ark., USA (<http://www.carlton-bates.com/index.shtml>).

As yet another example as shown in FIG. 1, FIG. 3, FIG. 5, FIG. 6, FIG. 7, and FIG. 8, aspects of embodiments and embodiments, the component 16 comprising a plurality of conductors comprises a printed circuit board (PCB).

As still yet another example, aspects of embodiments and embodiments, the indicia 20 adapted to provide guidance comprises a cross-reference between the pins or sockets the second connector 14 and a color of the third plurality of electrical conductors 32.

As even still yet another example, aspects of embodiments and embodiments, the third plurality of electrical conductors 32 comprise a plurality of cables and the indicia 20 adapted to provide guidance comprises a cross-reference between a color of the electrical conductors of each cable of the plurality

of cables and the pins or sockets each of the second 14, third 14', and fourth 14" connectors.

FIG. 4 is a schematic illustrating a use of the adapter 10 of FIG. 1 to electrically communicate with a nurse call station 40 electrically communicating with a plurality of hospital peripherals 44, 44', 44", 44", 44", and 44"" according to aspects of embodiments and/or embodiments of the present invention. However, FIG. 4 also illustrates why prior to the present invention, a skilled personal would require several hours to replace a worn and/or damaged connector. Namely, FIG. 4 shows that one make and model of nurse call station 40 removed from the wall with not only the third plurality of electrical conductors 32 from the worn and/or damaged connector but also the plurality of electrical conductors 54, 54', 54", 54", 54", and 54"" corresponding to the plurality of hospital peripherals 44, 44', 44", 44", 44", and 44"" (e.g., without limitation, include nurse and/or aide in the room station, dome light, code blue station, bath help station, emergency pull station, staff station, house keeping station, remote reset station, etc.).

Given that the third plurality of electrical conductors 32 can be 37 or more and if each of the plurality of hospital peripherals 44, 44', 44", 44", 44", and 44"" includes at least three conductors, conservatively, the number of conductors at a nurse call station 40 can be about 55. Applicant has encountered makes and models of nurse call stations 40 with to about 100 or more conductors. Just these number of conductors at a make and model of a nurse call stations 40 explains why unskilled and semi-skilled personal are incapable of replacing a connector having a plurality of pins or sockets electrically communicating through a plurality of electrical conductors in a predetermined pinout to facilitate electrical communication among preselected equipment 34 associated with a preselected hospital bed 36 (e.g., Stryker Medical, Portage, Mich., USA: see e.g., <http://www.stryker.com/en-us/products/PatientHandlingEMSSandEvacuationEquipment/Beds/index.htm> and <http://www.stryker.com/stellent/groups/jsp/documents/adacct/056403.pdf> as well as Hill-Rom Corporate Offices, Batesville, Ind., USA: <http://www.hill-rom.com/usa/index.asp> and <http://www.hill-rom.com/usa/PDF/CTG271.pdf>) and a preselected nurse station 40 (see e.g., Rauland-Borg Corporation, Mount Prospect, Ill., USA: <http://www.rauland.com/index.cfm>; Jeron Electronic Systems, Inc., Chicago, Ill., USA: <http://www.jeron.com/>; TekTone® Sound & Signal Mfg., Inc., Franklin, N.C., USA: <http://www.tektone.com/index.htm>; and Hill-Rom Corporate Offices, Batesville, Ind., USA: http://www.hill-rom.com/usa/NaviCare_NurseCall.htm that are merely four out of a possibility of about 25). Adding the further possibility of different makes and models of hospital beds 36 combined with different makes and models of nurse call stations 40 further combined with different hospital peripherals 44, 44', 44", 44", 44", and 44"" and again explains the challenges encountered by skilled personal.

FIG. 6 is schematic illustrating an adapter 10 of according to aspects of embodiments and/or embodiments of the present invention. Specifically, an adapter 10 was made using a type D sub connector having 37 contacts (Manufacturer Part No: 8LCM037S-304B-XX MULTICOMP, available from Newark of Chicago, Ill., USA as Part Number: 26M7826: see http://www.newark.com/multicomp/81_cm037s-304b-xx/socket-d-pcb-r-a-37way/dp/26M7826?Ntt=26M7826) and three different IDC connectors (5 Pin Connector CE-100-F-24-5-C; 8 Pin Connector CE-100-F-24-8-C; and 18 Pin Connector CE-100-F-24-18-C connect directly to their respective portions 18, 18', and 18" of the third plurality of electrical conductors 32 and called one of socket 26, 26', and 26" and

plug 24, 24', & 24") and their complementary IDC heddars (5 Pin hedder M-L-SS-100-5-C; 8 Pin Hedder M-L-SS-100-8-C; 18 Pin hedder M-L-SS-100-18-C, available from Carlton-Bates of Little Rock, Ark., USA (<http://www.carlton-bates.com/index.shtml>) connect directly to their respective portions 17, 17', and 17" of the plurality of conductors 28 of component 16 and called the other of socket 26, 26', and 26" and plug 24, 24', & 24") each mounted on a printed circuit broad configured with the plurality of conductors 28.

FIG. 8 is schematic illustrating an adapter 10 of according to aspects of embodiments and/or embodiments of the present invention. Specifically, an adapter 10 was made using a type D sub connector having 37 contacts (Manufacturer Part No: 8LCM037S-304B-XX MULTICOMP, available from Newark of Chicago, Ill., USA as Part Number: 26M7826: see http://www.newark.com/multicomp/81_cm037s-304b-xx/socket-d-pcb-r-a-37way/dp/26M7826?Ntt=26M7826), an IDC connectors (20 Pin Connector CE-100-F-24-20-C connect directly to its respective portion 18 of the third plurality of electrical conductors 32 and called one of socket 26, 26', and 26" and plug 24, 24', & 24") and its complementary IDC heddar (20 Pin Hedder M-L-SS-100-20-C, available from Carlton-Bates of Little Rock, Ark., USA (<http://www.carlton-bates.com/index.shtml>) connect directly to its respective portions 17 of the plurality of conductors 28 of component 16 and called the other of socket 26, 26', and 26" and plug 24, 24', & 24") appropriately mounted on a printed circuit broad configured with the plurality of conductors 28.

In operation, aspects of embodiments and embodiments of the present invention the first repair and/or replacement of worn and/or damaged connector can be quickly and easily performed by even unskilled personnel. That is, unskilled personnel, rather than recording the connection sequenced of the plurality of electrical conductors to the nurse call station 40, merely cuts the plurality of electrical conductors 32 at the mounting location on a lower portion of a wall at about shin level, removes the worn or damaged connector but not its associated plurality of electrical conductors 32, provides a new adapter 10, reconnects the associated plurality of electrical conductors 32 to the new adapter 10 according to indicia 20 sequenced using the tool 48, and replaces the new adapter 10 including the new connector 12. This process will have taken less than about 10 minutes. Subsequent repair and/or replacement of a worn and/or damaged connector can be performed by unskilled personnel even more quickly, i.e., less than 5 minutes, while requiring no previous knowledge of the adapter 10 or call station 40, and no special tools.

Other than in the operating examples, or where otherwise indicated, all numbers expressing quantities of ingredients, reaction conditions, and so forth used in the specification and claims are to be understood as being modified in all instances by the term "about." Accordingly, unless indicated to the contrary, the numerical parameters set forth in the following specification and attached claims are approximations that may vary depending upon the desired properties sought to be obtained by an aspect of an embodiment and/or embodiments of the present invention. At the very least, and not as an attempt to limit the application of the doctrine of equivalents to the scope of the claims, each numerical parameter should be construed in light of the number of significant digits and ordinary rounding approaches.

Notwithstanding that the numerical ranges and parameters setting forth the broad scope of the invention are approximations, the numerical values set forth in the specific examples are reported as precisely as possible. Any numerical values,

11

however, inherently contain certain errors necessarily resulting from the standard deviation found in their respective testing measurements.

ITEM LIST

	12
Adapter 10	Excel Digital, Hill-Rom 37-Pin, Nurse, TV, Vol., Channel UP/DN, 2 Lights, Version 4
First connector 12	Excel Digital, Hill-Rom 37-Pin, Nurse, TV, Vol., Channel UP/DN, Version 2
Second connector 14	5 Excel Entertainir, Hill-Rom 37-Pin, Nurse, TV, Vol., 10-Key & DVD/VCR, 2 Lights
Third connector 14'	Excel Entertainir, Hill-Rom 37-Pin, Nurse, TV, Vol., 10-Key & DVD/VCR, 2 Lights (Version 2)
Fourth connector 14"	Excel Entertainir, Hill-Rom 37-Pin, Nurse, TV, Vol., 10-Key, 1 Light
Component 16 comprising a plurality of conductors 28	Excel Entertainir, Hill-Rom 37-Pin, Nurse, TV, Vol., 10-Key, 2 Lights
First portion 17 of a third plurality of electrical conductors 32	Excel Entertainir, Hill-Rom 37-Pin, Nurse, TV, Vol., 10-Key, 2 Lights (Version 2)
Second portion 17' of a third plurality of electrical conductors 32	Excel Entertainir, Hill-Rom 37-Pin, Nurse, TV, Vol., 10-Key, 2 Lights (Version 3)
Third portion 17" of a third plurality of electrical conductors 32	Excel Entertainir, Hill-Rom 37-Pin, Nurse, TV, Vol., 10-Key, 2 Lights (Version 4)
Indicia 20	Excel Entertainir, Hill-Rom 37-Pin, Nurse, TV, Vol., 10-Key, 2 Lights (Version 5)
First portion 18 of the first plurality of pins or sockets 22	Excel Entertainir, Hill-Rom 37-Pin, Nurse, TV, Vol., 10-Key, 2 Lights (Version 6)
Second portion 18' of the first plurality of pins or sockets 22	Excel Entertainir, Hill-Rom 37-Pin, Nurse, TV, Vol., 10-Key, 2 Lights, Radio
Third portion 18" of the first plurality of pins or sockets 22	Excel LT, Hill-Rom 37-Pin, Nurse, TV, Vol.
First plurality of pins or sockets 22	Excel LT, Hill-Rom 37-Pin, Nurse, TV, Vol., 2 Lights
Plug 24, 24', 24"	Excel LT, Hill-Rom 37-Pin, Nurse, TV, Vol., 2 Lights, Radio
Socket 26, 26', 26"	Excel Digital, Hill-Rom 37-Pin, Nurse, TV, Vol. (POT), 10-Key
Plurality of conductors 28	Excel Digital, Hill-Rom 37-Pin, Nurse, TV, Vol. (POT), 10-Key, 2 Lights
Second plurality of pins or sockets 30	Excel Digital, Hill-Rom 37-Pin, Nurse, TV, Vol. (POT), 10-Key, 2 Lights, Version 2
Third plurality of pins or sockets 30'	35 Excel Digital, Hill-Rom 37-Pin, Nurse, TV, Vol. (POT), 10-Key, 2 Lights, Version 3
Fourth plurality of pins or sockets 30"	Excel Digital, Hill-Rom 37-Pin, Nurse, TV, Vol. (POT), 10-Key, 2 Lights, Version 4
Third plurality of electrical conductors 32	Excel Digital, Hill-Rom 37-Pin, Nurse, TV, Vol. (POT), Channel UP/DN
Preselected equipment 34	Excel Digital, Hill-Rom 37-Pin, Nurse, TV, Vol. (POT), Channel UP/DN, 2 Lights
Preselected hospital bed 36	Excel Digital, Hill-Rom 37-Pin, Nurse, TV, Vol., 10-Key
First predetermined pinout 38	Excel Digital, Hill-Rom 37-Pin, Nurse, TV, Vol., 10-Key, 2 Lights
Preselected nurse call station 40	40 . . . etc. might be configured and made.
Plurality of cables 42	It should be understood that all such modifications and improvements have been deleted herein for the sake of conciseness and readability but are properly within the scope of the following claims.
Peripherals 44, 44', 44", 44'', 44''', 44''''	The invention claimed is:
Ground 46	1. An adapter including
Tool 48 adapted to facilitate a mechanical communication Kit 50	(a) a first connector comprising a D-subminiature connector having a first plurality of pins or sockets;
While typical embodiments have been set forth for the purpose of illustration, the foregoing description should not be deemed to be a limitation on the scope of the invention. Accordingly, various modifications, adaptations, and alternatives may occur to one skilled in the art without departing from the spirit and scope of the present invention. By way of example, adaptors 10 for any one of:	(b) a second connector having:
Excel Digital, Hill-Rom 37-Pin, Nurse, TV, Vol., 10-Key, 2 Lights, Version 2	(i) a plug,
Excel Digital, Hill-Rom 37-Pin, Nurse, TV, Vol., 10-Key, 2 Lights, Version 3	(ii) a socket, and
Excel Digital, Hill-Rom 37-Pin, Nurse, TV, Vol., 10-Key, 2 Lights, Version 4	(iii) each plug and socket having a second plurality of pins or sockets,
Excel Digital, Hill-Rom 37-Pin, Nurse, TV, Vol., 10-Key, 2 Lights, Version 5	a. wherein one of the plug and the socket of the second connector is adapted to mechanically communicate
Excel Digital, Hill-Rom 37-Pin, Nurse, TV, Vol., 10-Key, 2 Lights, Version 6	
Excel Digital, Hill-Rom 37-Pin, Nurse, TV, Vol., 10-Key, Version 2	
Excel Digital, Hill-Rom 37-Pin, Nurse, TV, Vol., Channel UP/DN	
Excel Digital, Hill-Rom 37-Pin, Nurse, TV, Vol., Channel UP/DN, 2 Lights	
Excel Digital, Hill-Rom 37-Pin, Nurse, TV, Vol., Channel UP/DN, 2 Lights, Version 2	
Excel Digital, Hill-Rom 37-Pin, Nurse, TV, Vol., Channel UP/DN, 2 Lights, Version 3	

13

- with a first portion of a third plurality of electrical conductors to facilitate electrical communication while
- b. the other of the plug and the socket of the second connector is adapted to electrically communicate with a first portion of the first plurality of pins or sockets of the first connector; and
  - (c) a component comprising a plurality of conductors adapted for facilitating the other of the plug and the socket of the second connector to electrically communicate with the first portion of the first plurality of pins or sockets of the first connector in a first predetermined pinout.
2. The adapter according to claim 1, further including indicia adapted to provide guidance for the mechanical communication of the third plurality of electrical conductors to the one of the plug and the socket of the second connector to facilitate electrical communication of the third plurality of electrical conductors with the first portion of the first plurality of pins or sockets of the first connector in the predetermined pinout to facilitate electrical communication among preselected equipment associated with a preselected hospital bed and a preselected nurse call station.
3. The adapter according to claim 1, further including:
- (d) a third connector having:
    - (i) a plug,
    - (ii) a socket, and
    - (iii) each plug and socket having a third plurality of pins or sockets,
      - a. wherein one of the plug and the socket of the third connector is adapted to mechanically communicate with a second portion of the third plurality of electrical conductors to facilitate electrical communication while
      - b. the other of the plug and the socket of the third connector is adapted to electrically communicate with a second portion of the first plurality of pins or sockets of the first connector;
  - (e) a forth connector having:
    - (i) a plug,
    - (ii) a socket, and
    - (iii) each plug and socket having a forth plurality of pins or sockets,
      - a. wherein one of the plug and the socket of the fourth connector is adapted to mechanically communicate with a third portion of the third plurality of electrical conductors to facilitate electrical communication while
      - b. the other of the plug and the socket of the fourth connector is adapted to electrically communicate with a third portion of the first plurality of pins or sockets of the first connector; and
  - (f) indicia adapted to provide guidance for the mechanical communication of the third plurality of electrical conductors to the one of the plug and the socket of the second, third, and fourth connectors to facilitate electrical communication of the third plurality of electrical conductors with the first, second, and third portions of the first plurality of pins or sockets of the first connector in the predetermined pinout to facilitate electrical communication among preselected equipment associated with a preselected hospital bed and a preselected nurse call station,
- wherein the component comprising the plurality of conductors is adapted for facilitating the other of the plug and the socket of the second, third, and fourth connectors to electrically communicate with the first, second, and

14

- third portions of the first plurality of pins or sockets of the first connector in a first predetermined pinout.
4. The adapter according to claim 3, wherein any one of the third connector, the fourth connector, or the third and fourth connectors comprise any one of an insulation-displacement connector (IDC connector) or insulation-piercing connector (IPC connector).
5. The adapter according to claim 1, wherein the second connector comprises an insulation-displacement connector (IDC connector) or insulation-piercing connector (IPC connector).
- 10 6. The adapter according to claim 1, wherein the component comprising a plurality of conductors comprises a printed circuit board (PCB).
- 15 7. The adapter according to claim 1, wherein the indicia adapted to provide guidance comprises a cross-reference between the pins or sockets the second connector and a color of the third plurality of electrical conductors.
- 20 8. The adapter according to claim 3, wherein the third plurality of electrical conductors comprise a plurality of cables and wherein the indicia adapted to provide guidance comprises a cross-reference between a color of the electrical conductors of each cable of the plurality of cables and the pins or sockets each of the second, third, and fourth conductors.
- 25 9. A kit including:
- (a) an adapter including:
    - (i) a first connector comprising a D-subminiature connector having a first plurality of pins or sockets;
    - (ii) a second connector having
      - a. a plug,
      - b. a socket, and
      - c. each having a second plurality of pins or sockets,
        - i. wherein one of the plug and the socket of the second connector is adapted to mechanically communicate with a first portion of a third plurality of electrical conductors to facilitate electrical communication while
        - ii. the other of the plug and the socket of the second connector is adapted to electrically communicate with a first portion of the first plurality of pins or sockets of the first connector;
    - (iii) a component comprising a plurality of conductors adapted for facilitating the other of the plug and the socket of the second connector to electrically communicate with the first portion of the first plurality of pins or sockets of the first connector in a first predetermined pinout; and, optionally,

30

(b) a tool adapted to facilitate a mechanical communication of a third plurality of electrical conductors to one of a plug and a socket of a second connector to facilitate electrical communication of the third plurality of electrical conductors with a first portion of a first plurality of pins or sockets of a first connector.

35 10. A kit according to claim 9, further including indicia adapted to provide guidance for the mechanical communication of the third plurality of electrical conductors to the one of the plug and the socket of the second connector to facilitate electrical communication of the third plurality of electrical conductors with the first portion of the first plurality of pins or sockets of the first connector in the predetermined pinout to facilitate electrical communication among preselected equipment associated with a preselected hospital bed and a preselected nurse call station.

15

11. The kit according to claim 9, wherein the adapter further includes:

- (iv) a third connector having:
  - a. a plug,
  - b. a socket, and
  - c. each plug and socket having a third plurality of pins or sockets,
    - i. wherein one of the plug and the socket of the third connector is adapted to mechanically communicate with a second portion of the third plurality of electrical conductors to facilitate electrical communication while
    - ii. the other of the plug and the socket of the third connector is adapted to electrically communicate with a second portion of the first plurality of pins or sockets of the first connector;
- (v) a fourth connector having:
  - a. a plug,
  - b. a socket, and
  - c. each plug and socket having a fourth plurality of pins or sockets,
    - i. wherein one of the plug and the socket of the fourth connector is adapted to mechanically communicate with a third portion of the third plurality of electrical conductors to facilitate electrical communication while
    - ii. the other of the plug and the socket of the fourth connector is adapted to electrically communicate with a third portion of the first plurality of pins or sockets of the first connector; and
- (vi) indicia adapted to provide guidance for the mechanical communication of the third plurality of electrical conductors to the one of the plug and the socket of the second, third, and fourth connectors to facilitate electrical communication of the third plurality of electrical conductors with the first, second, and third portions of the first plurality of pins or sockets of the first connector in the predetermined pinout to facilitate electrical communication among preselected equipment associated with a preselected hospital bed and a preselected nurse call station,
  - wherein the component comprising the plurality of conductors is adapted for facilitating the other of the plug and the socket of the second, third, and fourth connectors to electrically communicate with the first, second, and third portions of the first plurality of pins or sockets of the first connector in a first predetermined pinout.

12. The kit according to claim 11, wherein any one of the third connector, the fourth connector, or the third and fourth connectors comprise any one of an insulation-displacement connector (IDC connector) or insulation-piercing connector (IPC connector).

13. The kit according to claim 9, wherein the second connector comprises an insulation-displacement connector (IDC connector) or insulation-piercing connector (IPC connector).

14. The kit according to claim 9, wherein the component comprising a plurality of conductors comprises a printed circuit board (PCB).

15. The kit according to claim 9, wherein the indicia adapted to provide guidance comprises a cross-reference between the pins or sockets of the second connector and a color of the third plurality of electrical conductors.

16. The kit according to claim 11, wherein the third plurality of electrical conductors comprise a plurality of cables and wherein the indicia adapted to provide guidance comprises a cross-reference between a color of the electrical

16

conductors of each cable of the plurality of cables and the pins or sockets each of the second, third, and fourth conductors.

17. A method for replacing a connector adapted to facilitate the electrical communication among preselected equipment associated with a preselected hospital bed and a preselected nurse, the method including:

- (a) providing an adapter, wherein the adapter includes:
    - (i) a first connector comprising a D-subminiature connector having a first plurality of pins or sockets;
    - (ii) a second connector having:
      - a. a plug,
      - b. a socket, and
      - c. each having a second plurality of pins or sockets,
        - i. wherein one of the plug and the socket of the second connector is adapted to mechanically communicate with a first portion of a third plurality of electrical conductors to facilitate electrical communication while
        - ii. the other of the plug and the socket of the second connector is adapted to electrically communicate with a first portion of the first plurality of pins or sockets of the first connector; and
    - (iii) a component comprising a plurality of conductors adapted for facilitating the other of the plug and the socket of the second connector to electrically communicate with the first portion of the first plurality of pins or sockets of the first connector in a first predetermined pinout; and
  - (b) communicating the third plurality of electrical conductors to the one of the plug and the socket of the second connector mechanical in a manner of the indicia.
18. The method according to claim 17, further comprising providing indicia adapted to provide guidance for the mechanical communication of the third plurality of electrical conductors to the one of the plug and the socket of the second connector to facilitate electrical communication of the third plurality of electrical conductors with the first portion of the first plurality of pins or sockets of the first connector in the predetermined pinout to facilitate electrical communication among preselected equipment associated with a preselected hospital bed and a preselected nurse call station, wherein the communicating the third plurality of electrical conductors to the one of the plug and the socket of the second connector mechanical is in a manner consistent with the indicia.
19. The method according to claim 17, wherein any one of:
- (a) the second connector comprises an insulation-displacement connector (IDC connector) or insulation-piercing connector (IPC connector);
  - (b) the component comprising a plurality of conductors comprises a printed circuit board (PCB); or
  - (c) the second connector comprises an insulation-displacement connector (IDC connector) or insulation-piercing connector (IPC connector) and the component comprising a plurality of conductors comprises a printed circuit board (PCB).
20. The method according to claim 18, wherein any one of:
- (d) the indicia adapted to provide guidance comprises a cross-reference between the pins or sockets of the second connector and a color of the third plurality of electrical conductors;
  - (e) the third plurality of electrical conductors comprise a plurality of cables and wherein the indicia adapted to provide guidance comprises a cross-reference between a color of the electrical conductors of each cable of a plurality of cables and the pins or sockets of each of the second conductor, a third conductor, and a fourth conductor; or
  - (f) both.

17

21. The method according to claim 17, wherein the adapter further includes:

- (iv) a third connector having:
  - a. a plug,
  - b. a socket, and
  - c. each plug and socket having a third plurality of pins or sockets,
    - i. wherein one of the plug and the socket of the third connector is adapted to mechanically communicate with a second portion of the third plurality of electrical conductors to facilitate electrical communication while
    - ii. the other of the plug and the socket of the third connector is adapted to electrically communicate with a second portion of the first plurality of pins or sockets of the first connector;
- (v) a fourth connector having:
  - a. a plug,
  - b. a socket, and
  - c. each plug and socket having a fourth plurality of pins or sockets,
    - i. wherein one of the plug and the socket of the fourth connector is adapted to mechanically communicate with a third portion of the third plurality of electrical conductors to facilitate electrical communication while
    - ii. the other of the plug and the socket of the fourth connector is adapted to electrically communicate with a third portion of the first plurality of pins or sockets of the first connector; and
- (vi) indicia adapted to provide guidance for the mechanical communication of the third plurality of electrical conductors to the one of the plug and the socket of the second, third, and fourth connectors to facilitate electrical communication of the third plurality of electrical conductors with the first, second, and third portions of the first plurality of pins or sockets of the first connector in the predetermined pinout to facilitate electrical communication among preselected equipment associated with a preselected hospital bed and a preselected nurse call station,
  - wherein the component comprising the plurality of conductors is adapted for facilitating the other of the plug and the socket of the second, third, and fourth connectors to electrically communicate with the first, second, and third portions of the first plurality of pins or sockets of the first connector in a first predetermined pinout.

22. The kit according to claim 21, wherein any one of the third connector, the fourth connector, or the third and fourth connectors comprise any one of an insulation-displacement connector (IDC connector) or insulation-piercing connector (IPC connector).

23. An adapter including

- (a) a first connector having a first plurality of pins or sockets;
- (b) a second connector having:
  - (i) a plug,
  - (ii) a socket, and
  - (iii) each plug and socket having a second plurality of pins or sockets,
    - a. wherein one of the plug and the socket of the second connector is adapted to mechanically communicate with a first portion of a third plurality of electrical conductors to facilitate electrical communication while

18

b. the other of the plug and the socket of the second connector is adapted to electrically communicate with a first portion of the first plurality of pins or sockets of the first connector, wherein the second connector comprises an insulation-displacement connector (IDC connector) or insulation-piercing connector (IPC connector); and

- (c) a component comprising a plurality of conductors adapted for facilitating the other of the plug and the socket of the second connector to electrically communicate with the first portion of the first plurality of pins or sockets of the first connector in a first predetermined pinout.

24. The adapter according to claim 23, further including indicia adapted to provide guidance for the mechanical communication of the third plurality of electrical conductors to the one of the plug and the socket of the second connector to facilitate electrical communication of the third plurality of electrical conductors with the first portion of the first plurality of pins or sockets of the first connector in the predetermined pinout to facilitate electrical communication among preselected equipment associated with a preselected hospital bed and a preselected nurse call station.

25. The adapter according to claim 23, further including:

- (d) a third connector having:
  - (i) a plug,
  - (ii) a socket, and
  - (iii) each plug and socket having a third plurality of pins or sockets,
    - a. wherein one of the plug and the socket of the third connector is adapted to mechanically communicate with a second portion of the third plurality of electrical conductors to facilitate electrical communication while
    - b. the other of the plug and the socket of the third connector is adapted to electrically communicate with a second portion of the first plurality of pins or sockets of the first connector;
- (e) a forth connector having:
  - (i) a plug,
  - (ii) a socket, and
  - (iii) each plug and socket having a forth plurality of pins or sockets,
    - a. wherein one of the plug and the socket of the fourth connector is adapted to mechanically communicate with a third portion of the third plurality of electrical conductors to facilitate electrical communication while
    - b. the other of the plug and the socket of the fourth connector is adapted to electrically communicate with a third portion of the first plurality of pins or sockets of the first connector; and
- (f) indicia adapted to provide guidance for the mechanical communication of the third plurality of electrical conductors to the one of the plug and the socket of the second, third, and fourth connectors to facilitate electrical communication of the third plurality of electrical conductors with the first, second, and third portions of the first plurality of pins or sockets of the first connector in the predetermined pinout to facilitate electrical communication among preselected equipment associated with a preselected hospital bed and a preselected nurse call station,
  - wherein the component comprising the plurality of conductors is adapted for facilitating the other of the plug and the socket of the second, third, and fourth connectors to electrically communicate with the first, second, and third portions of the first plurality of pins or sockets of the first connector to electrically communicate with the first, second, and third portions of the first plurality of pins or sockets of the first connector.

19

third portions of the first plurality of pins or sockets of the first connector in a first predetermined pinout.

26. The adapter according to claim **25**, wherein any one of the third connector, the fourth connector, or the third and fourth connectors comprise any one of an insulation-displacement connector (IDC connector) or insulation-piercing connector (IPC connector).

27. The adapter according to claim **25**, wherein any one of the second connector, the third connector, and the fourth connector comprise one of an insulation-displacement connector (IDC connector) and insulation-piercing connector (IPC connector) and any two other of the second connector, the third connector, and the fourth connector comprise the other of the insulation-displacement connector (IDC connector) and insulation-piercing connector (IPC connector).

28. The adapter according to claim **23**, wherein the component comprising a plurality of conductors comprises a printed circuit board (PCB).

29. The adapter according to claim **23**, wherein the indicia adapted to provide guidance comprises a cross-reference between the pins or sockets the second connector and a color of the third plurality of electrical conductors.

30. The adapter according to claim **25**, wherein the third plurality of electrical conductors comprise a plurality of cables and wherein the indicia adapted to provide guidance comprises a cross-reference between a color of the electrical conductors of each cable of the plurality of cables and the pins or sockets each of the second, third, and fourth conductors.

31. A kit including:

(a) an adapter including:

- (i) a first connector having a first plurality of pins or sockets;
- (ii) a second connector having
  - a. a plug,
  - b. a socket, and
  - c. each having a second plurality of pins or sockets,
    - i. wherein one of the plug and the socket of the second connector is adapted to mechanically communicate with a first portion of a third plurality of electrical conductors to facilitate electrical communication while
    - ii. the other of the plug and the socket of the second connector is adapted to electrically communicate with a first portion of the first plurality of pins or sockets of the first connector, wherein the second connector comprises an insulation-displacement connector (IDC connector) or insulation-piercing connector (IPC connector);

(iii) a component comprising a plurality of conductors adapted for facilitating the other of the plug and the socket of the second connector to electrically communicate with the first portion of the first plurality of pins or sockets of the first connector in a first predetermined pinout; and, optionally,

(b) a tool adapted to facilitate a mechanical communication of a third plurality of electrical conductors to one of a plug and a socket of a second connector to facilitate electrical communication of the third plurality of electrical conductors with a first portion of a first plurality of pins or sockets of a first connector.

32. A kit according to claim **31**, further including indicia adapted to provide guidance for the mechanical communication of the third plurality of electrical conductors to the one of the plug and the socket of the second connector to facilitate electrical communication of the third plurality of electrical conductors with the first portion of the first plurality of pins or sockets of the first connector in the predetermined pinout to

20

facilitate electrical communication among preselected equipment associated with a preselected hospital bed and a preselected nurse call station.

33. The kit according to claim **31**, wherein the adapter further includes:

- (iv) a third connector having:
  - a. a plug,
  - b. a socket, and
  - c. each plug and socket having a third plurality of pins or sockets,
    - i. wherein one of the plug and the socket of the third connector is adapted to mechanically communicate with a second portion of the third plurality of electrical conductors to facilitate electrical communication while
    - ii. the other of the plug and the socket of the third connector is adapted to electrically communicate with a second portion of the first plurality of pins or sockets of the first connector;
- (v) a fourth connector having:
  - a. a plug,
  - b. a socket, and
  - c. each plug and socket having a fourth plurality of pins or sockets,
    - i. wherein one of the plug and the socket of the fourth connector is adapted to mechanically communicate with a third portion of the third plurality of electrical conductors to facilitate electrical communication while
    - ii. the other of the plug and the socket of the fourth connector is adapted to electrically communicate with a third portion of the first plurality of pins or sockets of the first connector; and

(vi) indicia adapted to provide guidance for the mechanical communication of the third plurality of electrical conductors to the one of the plug and the socket of the second, third, and fourth connectors to facilitate electrical communication of the third plurality of electrical conductors with the first, second, and third portions of the first plurality of pins or sockets of the first connector in the predetermined pinout to facilitate electrical communication among preselected equipment associated with a preselected hospital bed and a preselected nurse call station,

wherein the component comprising the plurality of conductors is adapted for facilitating the other of the plug and the socket of the second, third, and fourth connectors to electrically communicate with the first, second, and third portions of the first plurality of pins or sockets of the first connector in a first predetermined pinout.

34. The kit according to claim **33**, wherein any one of the third connector, the fourth connector, or the third and fourth connectors comprise any one of an insulation-displacement connector (IDC connector) or insulation-piercing connector (IPC connector).

35. The kit according to claim **31**, wherein any one of the second connector, the third connector, and the fourth connector comprise one of an insulation-displacement connector (IDC connector) and insulation-piercing connector (IPC connector) and any two other of the second connector, the third connector, and the fourth connector comprise the other of the insulation-displacement connector (IDC connector) and insulation-piercing connector (IPC connector).

36. The kit according to claim **31**, wherein the component comprising a plurality of conductors comprises a printed circuit board (PCB).

21

37. The kit according to claim 31, wherein the indicia adapted to provide guidance comprises a cross-reference between the pins or sockets of the second connector and a color of the third plurality of electrical conductors.

38. The kit according to claim 33, wherein the third plurality of electrical conductors comprise a plurality of cables and wherein the indicia adapted to provide guidance comprises a cross-reference between a color of the electrical conductors of each cable of the plurality of cables and the pins or sockets each of the second, third, and fourth conductors.

39. A method for replacing a connector adapted to facilitate the electrical communication among preselected equipment associated with a preselected hospital bed and a preselected nurse, the method including:

(a) providing an adapter, wherein the adapter includes:

(i) a first connector having a first plurality of pins or sockets;

(ii) a second connector having:

a. a plug,

b. a socket, and

c. each having a second plurality of pins or sockets,

i. wherein one of the plug and the socket of the second connector is adapted to mechanically communicate with a first portion of a third plurality of electrical conductors to facilitate electrical communication while

ii. the other of the plug and the socket of the second connector is adapted to electrically communicate with a first portion of the first plurality of pins or sockets of the first connector, wherein the second connector comprises an insulation-displacement connector (IDC connector) or insulation-piercing connector (IPC connector); and

(iii) a component comprising a plurality of conductors adapted for facilitating the other of the plug and the socket of the second connector to electrically communicate with the first portion of the first plurality of pins or sockets of the first connector in a first predetermined pinout; and

(b) communicating the third plurality of electrical conductors to the one of the plug and the socket of the second connector mechanical in a manner of the indicia.

40. The method according to claim 39, further comprising providing indicia adapted to provide guidance for the mechanical communication of the third plurality of electrical conductors to the one of the plug and the socket of the second connector to facilitate electrical communication of the third plurality of electrical conductors with the first portion of the first plurality of pins or sockets of the first connector in the predetermined pinout to facilitate electrical communication among preselected equipment associated with a preselected hospital bed and a preselected nurse call station, wherein the communicating the third plurality of electrical conductors to the one of the plug and the socket of the second connector mechanical is in a manner consistent with the indicia.

41. The method according to claim 39, wherein any one of:

(α) the indicia adapted to provide guidance comprises a cross-reference between the pins or sockets of the second connector and a color of the third plurality of electrical conductors;

(β) the third plurality of electrical conductors comprise a plurality of cables and wherein the indicia adapted to provide guidance comprises a cross-reference between a color of the electrical conductors of each cable of a

22

plurality of cables and the pins or sockets of each of the second conductor, a third conductor, and a fourth conductor; or

(χ) both.

42. The method according to claim 40, wherein the adapter further includes:

(iv) a third connector having:

a. a plug,

b. a socket, and

c. each plug and socket having a third plurality of pins or sockets,

i. wherein one of the plug and the socket of the third connector is adapted to mechanically communicate with a second portion of the third plurality of electrical conductors to facilitate electrical communication while

ii. the other of the plug and the socket of the third connector is adapted to electrically communicate with a second portion of the first plurality of pins or sockets of the first connector;

(v) a fourth connector having:

a. a plug,

b. a socket, and

c. each plug and socket having a fourth plurality of pins or sockets,

i. wherein one of the plug and the socket of the fourth connector is adapted to mechanically communicate with a third portion of the third plurality of electrical conductors to facilitate electrical communication while

ii. the other of the plug and the socket of the fourth connector is adapted to electrically communicate with a third portion of the first plurality of pins or sockets of the first connector; and

(vi) indicia adapted to provide guidance for the mechanical communication of the third plurality of electrical conductors to the one of the plug and the socket of the second, third, and fourth connectors to facilitate electrical communication of the third plurality of electrical conductors with the first, second, and third portions of the first plurality of pins or sockets of the first connector in the predetermined pinout to facilitate electrical communication among preselected equipment associated with a preselected hospital bed and a preselected nurse call station,

wherein the component comprising the plurality of conductors is adapted for facilitating the other of the plug and the socket of the second, third, and fourth connectors to electrically communicate with the first, second, and third portions of the first plurality of pins or sockets of the first connector in a first predetermined pinout.

43. The kit according to claim 42, wherein any one of the third connector, the fourth connector, or the third and fourth connectors comprise any one of an insulation-displacement connector (IDC connector) or insulation-piercing connector (IPC connector).

44. The kit according to claim 42, wherein any one of the second connector, the third connector, and the fourth connector comprise one of an insulation-displacement connector (IDC connector) and insulation-piercing connector (IPC connector) and any two other of the second connector, the third connector, and the fourth connector comprise the other of the insulation-displacement connector (IDC connector) and insulation-piercing connector (IPC connector).
